UNITED STATES PATENT OFFICE.

NEVVENS N. NUNN, OF MAPLEWOOD, MISSOURI, ASSIGNOR TO THE ALMETAL MANUFACTURING COMPANY, OF MAPLEWOOD, MISSOURI, A CORPORATION OF MISSOURI.

WASHING-MACHINE.

1,164,851.

Specification of Letters Patent. Patented Dec. 21, 1915.

Application filed March 20, 1915. Serial No. 15,939.

To all whom it may concern:

Be it known that I, NEVVENS N. NUNN, a citizen of the United States, residing at Maplewood, St. Louis county, Missouri, have 5 invented a certain new and useful Improvement in Washing-Machines, of which the following is a full, clear, and exact description, such as will enable others skilled in the art to which it appertains to make and use 10 the same, reference being had to the accompanying drawings, forming part of this specification, in which—

My invention relates to washing machines of the type disclosed in U. S. Letters Patent 15 No. 566,885, dated September 1, 1896, wherein a boiler, which is equipped with a manually operated clothes pounder, is combined with a laundry stove or heater, the principal object of my invention being to 20 generally improve upon and simplify the construction of this particular type of washing machine, and to provide certain novel features of construction which will render the machine more effective in use and reduce 25 to a minimum the labor and fuel expense incident to the laundrying operations.

Further objects of my invention are, to provide the boiler with pounding or rubbing members which are corrugated in order to 30 materially increase their clothes engaging surfaces, and consequently increasing the efficiency of said pounding or rubbing members; to arrange the bearing for the pounder carrying rod at a point substantially above 35 the top of the boiler so that the water within the boiler cannot come in contact with said bearing, which action would result in discoloration of the water; to provide a readily removable rubbing member in the lower portion 40 of the boiler against which the clothes are pressed by the pounder during the washing operation, and further, to provide a removable member for the upper end of the stove, which member receives the lower portion 45 of the boiler, and said removable member being provided with a removable plate which serves as a support for flat irons while the same are being heated.

With the foregoing and other objects in 50 view, my invention consists in certain novel features of construction and arrangement of parts, hereinafter more fully described,

claimed and shown in the accompanying drawings, in which—

Figure 1 is a vertical sectional view taken 55 through the center of a washing machine of my improved construction. Fig. 2 is a horizontal section taken approximately on the line 2—2 of Fig. 1. Fig. 3 is a detail sectional view of the boiler holding member 60 which is removably positioned in the upper portion of the stove and showing the removable plate in the bottom of said member. Fig. 4 is a plan view of the bottom of the 65 boiler and showing the retaining means for the corrugated rubbing member which is positioned within said boiler. Fig. 5 is an enlarged horizontal section taken approximately on the line 5—5 of Fig. 1.

Referring by numerals to the accompanying drawings, 10 designates the body of the stove, the same being in the form of a vertically disposed cylinder provided in its bottom with a grate 11 below which is positioned a removable ash pan 12.

A firing door 13 normally closes an opening in the lower portion of the front of the stove and leading from the upper rear portion of the body 10 is a pipe 14 for conveying off the smoke and products of combustion.

Projecting inwardly from the upper portion of the body 10 of the stove is a series of brackets 15 which serve as supports for the lower end of a pan-shaped member 16, the same being provided with a large circular opening 17 in its bottom and having an outwardly projecting flange 18 at its upper edge which is adapted to rest on the upper edge of the body 10.

A removable plate 19 is adapted to close 90 the opening in the bottom of the member 16, which plate is in the nature of an ordinary stove lid.

The boiler 20 of my improved machine is preferably constructed of sheet metal in cylindrical form and tapered slightly toward its lower end, which latter portion is of such size as to fit snugly within the member 16. The upper portion of the boiler is adapted to be closed by a cover 21 in the center of which 95 is formed an opening 22.

Fixed to the central portion of the cover 21 and projecting upwardly therefrom is a bracket 23 provided at its upper end with a

vertically disposed bearing 24 and operating therein is a vertically disposed rod or tube 25, the same extending downward through the opening 22. The relative diameters of 5 the rod 25 and opening 22 are such that the rod 25 in its vertical movement does not touch the edge of the cover around said opening 22.

Fixed to one side of the cover 21 is a post 10 or standard 26, to the upper end of which is pivotally connected one end of a hand lever 27, the same extending across the top of the boiler and being pivotally connected to the rod 25. There is sufficient play in the 15 pivotal connection between the lever 27 and rod 25 to permit the latter to move freely through its bearing 24 as the hand lever is vibrated vertically.

Fixed to the lower end of rod 25 is a low conical pounding or rubbing member 28, the same being radially corrugated in order 20 to materially increase its rubbing surface, and formed near the upper end of this member is a series of small apertures 29. Positioned 25 on the upper end of this member is a small conical disk 30 having upwardly bent portions 31 which overlie the apertures 29. This construction permits the escape of air which may be trapped in the upper portion 30 of the member 21 during its downward movement, and likewise permits air to enter the upper portion of the pounding member during its downward movement, and the overlying portions 31 of disk 30 prevents 35 the air outlet openings 29 from being closed by the clothes within the machine during the upward movement of the pounding member. The pounding member 28 and disk 30 are preferably constructed of sheet metal 40 or like material.

Removably positioned within the boiler 20 and upon the bottom thereof is a frusto-conical rubbing member 32 which is constructed of sheet metal or analogous material, said member being radially corrugated 45 so as to increase its effectiveness when the clothes are forced downward onto its top surface by the pounder 28 and said rubbing member is held in fixed position in 50 the bottom of the boiler by means of a locking member, the same comprising a ring 33 which bears on top of the member 32, and said ring being provided with a depending portion 34 on which is formed a pair of 55 oppositely disposed outwardly projecting lugs or fingers 35.

Fixed on the central portion of the bottom of the boiler 20 is a ring 36, the upper edge of which is provided with a pair of 60 inwardly projecting oppositely inclined flanges 37. Openings 38 are provided between the ends of these flanges to permit the insertion of the lugs 35 carried by the locking member and when the latter is rotated 65 approximately a quarter turn, said lugs bear

against the undersides of flanges 37, and consequently drawing ring 33 downward so as to rigidly retain member 32 in position on the bottom of the boiler.

When the boiler is located on the stove 70 plate 19 is removed from member 16, and thus the heat from the fire within the stove comes in direct contact with the bottom of the boiler, thereby heating the water therein. The clothes to be washed are placed 75 in the water within the boiler and distributed over the top of member 32. The operator now manually engages hand lever 27 and vibrates the same vertically, thereby imparting reciprocating movement to rod 25 80 and the pounder 28 carried by the lower end thereof in its downward movement bears upon the mass of clothes resting upon member 32, and forces water and air through 85 said clothes to effect the cleansing thereof. It will be noted that the bearing 24 for 90 the rod 25 is located a substantial distance above the top of the boiler and that said rod in its vertical movement does not touch the material forming the boiler top 95 21, and thus the water which may splash upward during the operation of the machine will not become discolored as would be the case where said water comes in contact with an oily bearing.

The member 32 is retained in proper position in the bottom of the boiler by the locking member comprising the parts 32 and 34 and when it is desired to clean the interior of the boiler, said locking member 100 can be readily detached to permit the removal of the rubbing member.

When it is desired to heat flat irons or heat water in a comparatively small receptacle, the plate 19 is positioned in the lower 105 portion of member 16, thus providing a flat surface of ample area which is directly acted upon by the heat from the fire within the stove forming a part of my improved apparatus. Thus, it will be seen that I 110 have combined in a single structure, a laundry stove, a washing machine, and a boiler which structure is comparatively simple, can be easily and cheaply manufactured, is time and labor saving, and particularly economical in point of fuel consumption.

It will be readily understood that minor changes in the size, form and construction of the various parts of my improved device can be made and substituted for those herein shown and described, without departing from the spirit of my invention, the scope of which is set forth in the appended claim:

I claim:

In a washing machine, a boiler, a frusto-conical rubbing member positioned on the bottom thereof, there being an opening in the center of said rubbing member, a ring 120 fixed on the bottom of the boiler, which ring is provided with inwardly projecting 125

flanges, and a locking member for the rubbing member, which locking member comprises a ring adapted to bear on top of said rubbing member, a body portion depending from said ring, and lugs on said body portion which are adapted to engage beneath the flanges of the ring on the bottom of the boiler to lock the rubbing member thereto.

In testimony whereof I hereunto affix my signature in the presence of two witnesses, ¹⁰ this 15th day of March, 1915.
